DESIGN FOR A LIGHTING FIXTURE BODY

Peter Parlato, Astoria, N. Y., assignor to Pareo
Lighting Equipment Co., Inc., New York, N. Y.,
a corporation of New York

Application August 6, 1937, Serial No. 70,879

Term of patent 3½ years

To all whom it may concern:

Be it known that I, Peter Parlato, a citizen of the United States of America and a resident of Astoria, in the county of Queens and State of New York, have invented a new, original, and ornamental Design for a Lighting Fixture Body, of which the following is a specification, reference being had to the accompanying drawing, forming a part thereof.

The figure is a side elevational view partly in section of a lighting fixture body showing my new design.

The design is characterized by a lighting fixture body of substantially the contour shown and having a series of closely spaced louvers grouped midway of the height of the body and which extend beyond the contour of the body.

I claim:

The ornamental design for a lighting fixture body, as shown and described.

PETER PARLATO.
